UNITED STATES PATENT OFFICE

SAMUEL TAVALIN, OF ASTORIA, NEW YORK

BRUSH

Application filed May 15, 1930. Serial No. 452,552.

The present invention relates to brushes and more particularly to an improved fountain brush.

It is customary to wash the wheels and mudguards of motor vehicles by spraying water thereon. In most instances, mud has been splashed on the wheels and has caked thereon, in which case the wheels are extremely difficult to clean and it is necessary to apply a brush in conjunction with the water to remove the foreign substances. The person cleaning the car must use both a water hose and a brush at the same time. Such procedure is inconvenient and cumbersome.

Various brushes have been devised, which have means for spraying water from the brush member. These constructions generally comprise a hollow block having bristles bound therein, apertures intermediate the bristles, a cover member adapted to seal the hollow reservoir, and means connecting a supply of water to the reservoir. A gasket usually extends substantially about the periphery of the cover to make a water-tight seal between the block and the cover. A relatively large and expensive gasket is necessary because it is the sole seal holding the water in the brush. Such a gasket must be replaced frequently because any leak will impair the brush. The bindings of the bristles of the brush extend directly into the reservoir and are constantly subjected to the liquid, which impairs the bindings and causes the bristles to fall out, thus shortening the useful life of the brush. These, and other defects, render such brushes impractical.

The present invention aims to eliminate the difficulties enumerated above by providing a member within the block of the brush adapted to distribute a fluid through conduits within, and preferably centrally disposed with respect to the individual bristle members. A liquid reservoir is omitted entirely and the bindings of the brushes are kept substantially dry at all times, whereby the life of the brush is increased substantially and its effectiveness in removing dirt is enhanced.

An object of the present invention is to provide an inexpensive fountain brush adapted to spray a stream of water effectively and efficiently through the brush members.

Another object of the invention is to eliminate the use of reservoirs by providing distributing means which connect directly with the hose and extend through the brush members, whereby the bindings of the bristles are kept substantially dry at all times.

Another object of the invention is to eliminate expensive gaskets by providing means wherein leaks have little effect and replacements can be made at a very slight cost.

A further object of the invention is to provide a brush construction having a set of permanent bristles in the block portion and a plurality of replaceable brush members forming a substantial part of the brush, which is subjected to the most wear, to facilitate replacement of worn parts.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification, wherein

Fig. 1 is a side elevational view of a preferred embodiment of the present invention;

Fig. 2 is a top plan view of the brush construction with the cover portion partially broken away to show the assembled members within the brush;

Fig. 3 is a sectional view taken along the line 3—3 of Fig. 2;

Fig. 4 is a top plan view illustrating the block of the brush with the cover and liquid connections removed;

Fig. 5 is an enlarged perspective view of the distributing member; and

Fig. 6 is an enlarged perspective view of one of the brush members.

Referring again to the drawings, and more particularly to Figs. 1, 2, 3 and 4, there is shown a block member 1, constructed of hard wood, bakelite, or like material, having a recessed portion 2 formed in the upper surface thereof to provide a suitable casing for devices to be described hereinafter. The block may be of any desired shape, but is shown herein as substantially rectangular or oblong. A ridge 4 extends about the recessed portion 2 and merges into the body of the block at 5 and 6, respectively. A channel or groove 7 extends longitudinally through the front end of the block and along the bottom of the recess 2, providing a channel for a handle and its associated parts encased in the recess 2. A shoulder 9, formed at the lower sides of the block 1, extends about the periphery thereof and facilitates the application of a suitable cover to the side portions 10 immediately above and in line with the shoulder 9.

A plurality of openings 11 are provided in the block adjacent the inner side walls of the ridge 4, preferably in two rows, extending about the outer periphery of the recessed portion 2. The openings 11 are adapted to receive a series of bristles 12, which are bound or glued therein in any suitable manner. At the central portion of the recess or casing 2, a plurality of enlarged openings 14 are provided, herein shown as five in number. These openings extend transversely through the block 1 and are adapted to receive a corresponding number of brush members 15, which are preferably secured therein by a suitable adhesive or rubberized compound. The brush members 15 occupy substantially the central portion of the brush and are adjacent the outer and smaller bristle units 12 disposed in the openings 11. It will, of course, be understood that the present invention is not limited to any particular number of brush members as any convenient number may be used, depending upon the size of the block. The central brush members 15 are slightly longer than the brush members 12 and, hence, are adapted to do the bulk of the brushing operation.

Fig. 6 serves to illustrate the details of one of the brush members of the embodiment. These members are adapted to permit a stream of fluid to be sprayed through the bristles thereof and, to achieve this result, the brush members 15 comprise a small metal tube 16 having bristles 17 securely bound thereabout in any suitable manner. The width of the binding wrapper 19, utilized herein, corresponds to the thickness of the block 1 at the apertures 14, so that the members 15 may be suitably fastened thereto and be readily removed and replaced. Prefer-

ably, the conduits or tubes 16 are glued or cemented to the bristles 17 and extend through the binding to a point substantially below it, whereby the binding will be separated from the stream of fluid ejected through the conduits and subjected to the least possible amount of water. By shielding the binding from the water, the life thereof is prolonged.

In order to distribute a fluid such as water or cleaning solution to the conduits 16, there is provided a tube or pipe 20, which serves as the handle for the brush and is adapted to be encased within the recess 2 and the groove 7. The handle 20 has, at its forward end 21, a series of branch members 22 spaced to fit into the conduits 16 within the brush members 15. The branches 22 may be connected to the tube 20 by providing apertures 24 in the tube and soldering or brazing the branches therein. The tip of the tube 25 may be closed by a suitable cap 26 having a branch member disposed therein, or in any other suitable manner. Preferably, the tube and the branch members are constructed of a serviceable metal, such as copper, which is strong and durable and will not be affected by corrosion.

The branch members may comprise a relatively small copper tube bent into the shape of an elbow, having one end secured to the main tube 20 and having the free end or nipple 27 projecting downwardly to fit into the conduits 16. The outer diameter of the nipple portions 27 is slightly smaller than the inner diameter of the conduits 16, thus permitting the nipples 27 to be inserted therein. Above the nipple portions 27 of the branches, flange portions 29 are provided to support suitable gasket members 30. When the tube 20 is assembled within the casing 2, the nipples project downwardly into the conduits 16 and the gaskets are compressed between the flanges 29 and the upper ends of the conduits to form a seal therewith. The liquid-tight joints between the nipples and tubes 16 prevent access of water to the upper ends of the brushes 15 and to the binding material therein. They also eliminate the necessity for a liquid-tight enclosure about the recess 2. The tube 20 may be fastened to the block 1 by means of a strip of metal 31 extending about the tube and fastened by suitable screws 32 to the block.

The tube 20 may be of any convenient length, the portion thereof extending outwardly beyond the block serving as a handle for the brush. Substantially at the end of the tube, a grip member 35, preferably of rubber, is provided to facilitate holding the handle. At the end of the tube, a threaded portion is provided, which is adapted to engage a coupling 37 attached to a hose 39. A valve or pet cock 40 may be connected in

the hose line adjacent to the coupling for the person using the brush to regulate the water supply delivered thereto.

To complete the construction of the casing, 5 a removable cover 41, preferably formed of thin metal, is provided. The cover comprises a top portion 42 and a depending peripheral skirt 44 adapted to be telescoped about the side portion 10 above the shoulder 10 of the block. A slot 45 is provided in the skirt at the groove 7 to permit the tube 20 to pass outwardly therethrough. The cover 41 is secured to the block by suitable screws 46 extending through the skirt 44 into the 15 side walls of the block. In this manner, the cover may be readily removed to inspect or replace the brushes or other parts.

To insure a leak-proof construction, a suitable gasket 47 is interposed between the 20 cover and the ridge 4 and the body of the block at 5 and 6. A packing 48 may also be provided at the groove 7 between the brush block and the pipe 20. The gasket 47 and packing 48 form a substantial double 25 seal about the distributing members but are not necessary as the seal between the branches 22 and tubes 16 is sufficient to render the construction water-tight.

In using the brush, the parts thereof are 30 assembled as indicated in the drawings. The hose 39 is connected to a suitable supply of water or soap solution and the liquid therein is permitted to flow through the hose. The valve 40 is then regulated to obtain the 35 desired pressure within the pipe or tube 20. The liquid flows directly from the tube 20 through the branches 22 to the tubes 16 which spray the liquid through the brush members 15. The brush is then gripped by 40 the handle 20 at the holding member 35 and manipulated in the proper manner to brush the surface desired to be cleaned. If more or less water is required, the valve 40 can readily be adjusted without interrupting the 45 brushing operation.

It will be seen that the present invention provides an inexpensive fountain brush construction which is particularly adapted to be used for scrubbing mud spattered surfaces, 50 such as automobile bodies, fenders and the like. The liquid is distributed to the brush member and is sprayed therethrough in an efficient manner, whereby leaks are eliminated and the wear of the brushes is minimized. By connecting the tube 20 directly 55 to the small tubes 16 extending through the brushes, the bindings of the bristles are not subjected to the liquid and the bristles and binding will not rot or become otherwise impaired. The brush may be readily disassembled for repair or replacement of parts 60 without returning it to the factory. The parts of the brush are rugged in construction and fully capable of withstanding the rough 65 usage to which they may be subjected.

As various changes may be made in the form, construction and arrangement of parts herein without departing from the spirit and scope of the invention and without sacrificing its advantages, it is to be understood that 70 all matter herein is to be interpreted as illustrative and not in a limiting sense.

Having thus described my invention, I claim:

1. In a brush, the combination of a block 75 having bristles permanently secured therein, a plurality of apertures in said block, brush members disposed in said apertures, said members comprising a tube having bristles circumferentially secured thereabout, and a 80 pipe member connected to a supply of water by suitable means, said pipe having a plurality of branches adapted to engage said conduits within said brush members, whereby water may be ejected through said brush 85 members.

2. In a brush, the combination of a block having bristles permanently secured therein, a plurality of apertures in the central portion of said block, removable brush members 90 disposed in said apertures, said members comprising a metal tube extending below the binding of said brush member having bristles circumferentially secured thereabout, and a pipe member connected to a supply of 95 water by suitable means, said pipe having a plurality of distributing branches adapted to engage said conduits within said brush members, whereby water may be ejected through said brush members. 100

3. In a brush, the combination of a block, a plurality of brush members disposed in said block, some of said members having a conduit in the central portion thereof, and means for dispensing cleaning solutions 105 through said brushes, said means comprising a pipe member secured to said block with a plurality of distributing branches projecting therefrom, flange portions on said branches, and sealing means for forming a 110 liquid-tight seal between said distributing branches and conduits within said brush members.

4. In a brush, the combination of a block, a plurality of brush members disposed in 115 said block, some of said members having a conduit in the central portion thereof extending below the butt of said members, and means for dispensing cleaning solutions through said members, said means comprising a pipe member secured to said block with a plurality of distributing branches projecting therefrom, flange portions on said branches, and sealing means for forming a 120 liquid-tight seal between said distributing branches and conduits within said brush members, and rows of brush members extending about said first mentioned brush members. 125

5. In a brush of the class described, the 130

combination of a block member, a pipe en-
cased in said member for dispensing fluids
through the bristles of said brush, a plurality
5 of distributing members secured to said
pipe, and a plurality of brush members
adapted to receive said distributing mem-
bers, whereby said fluid may be discharged
through said brush.

6. In a brush of the class described, the
10 combination of a tube for dispensing a fluid,
said tube having a plurality of branches ar-
ranged in pairs and extending transversely
thereof, a plurality of removable brush
15 units mounted below said tube comprising
suitable bristles, and a metal tube extending
through the central portion of said bristles
and passing below the binding thereof, and
means for connecting said branches and
conduits.

20 7. In a brush of the class described, the
combination of a block having a recessed
portion therein, brush members mounted in
said block, certain of said brush members
having conduits therein, a tube disposed in
25 said recessed portion having means adapted
to be connected to said conduits within said
brush members, and a cover portion adapted
to close said recessed portion of the block.

8. In a scrubbing brush of the class de-
30 scribed, the combination of block member
means for dispensing cleaning solutions,
said means comprising a pipe member, a
plurality of distributing members secured to
35 said pipe, flange portions on said members,
and a suitable gasket mounted below said
flange portions adapted to abut thereagainst,
and a plurality of brush members mounted
40 in said block member having tubes therein
adapted to receive first said conduits, where-
by the cleaning solution may be dispensed
through said brushes.

9. In a brush of the class described, the
combination of a plurality of brush mem-
bers having conduits therein, a pipe mem-
45 ber adapted to be connected to a source of
fluid, a plurality of hollow downwardly pro-
jecting members arranged bilaterally with
respect to said pipe, and means for connect-
ing said projecting members directly to said
50 conduits.

10. In a brush of the class described, the
combination of a block member, a pipe
adapted to serve as a handle for the brush,
55 tubular branches leading from said pipe, a
series of brush units having a tube with
bristles secured thereabout disposed in said
block member, said tubes being adapted to
receive the ends of said tubular branches,
60 and means for forming liquid-tight joints
between said branches and said tubes.

SAMUEL TAVALIN.
